UNITED STATES PATENT OFFICE.

NYKOLA PETRYK, OF PHILADELPHIA, PENNSYLVANIA.

SMOKE-CONSUMER FOR LOCOMOTIVES.

1,243,214.

Specification of Letters Patent. Patented Oct. 16, 1917.

Application filed January 6, 1917. Serial No. 140,879.

To all whom it may concern:

Be it known that I, NYKOLA PETRYK, a subject of the Emperor of Austria, residing at Philadelphia, in the county of Philadelphia and State of Pennsylvania, have invented certain new and useful Improvements in Smoke-Consumers for Locomotives, of which the following is a specification.

This invention relates to new and useful improvements in smoke consumers for locomotives.

The primary object of the invention is the provision of a device for locomotives whereby the products of combustion will be washed and cleaned of cinders, carbon and other impurities prior to being exhausted to the atmosphere, the device being in the nature of a smoke consumer reducing the amount of smoke escaping from a locomotive.

A further object of the device is to provide a spray chamber upon a locomotive through which the products of combustion must pass on their way from the heating flues to the outlet stack, provision being made for drawing off the cinders and dirt deposited within the chamber from the gases passing therethrough.

In the drawing forming a part of this application and in which like reference characters refer to corresponding parts throughout the several views,

Figure 1 is a side elevation of a locomotive boiler provided with the present device, parts being broken away,

Fig. 2 is a top plan view of a portion of the locomotive and present improvement in operative position thereon, and

Figs. 3 and 4 are vertical transverse sectional views taken upon lines III—III and IV—IV of Fig. 1.

The present device for washing the products of combustion emanating from a firebox is adaptable for locomotive boilers, and is herein illustrated in connection with such a locomotive 10 having fire tubes 11 and a smoke box 12. A housing 13 is mounted upon the locomotive 10 and has a washing chamber 14 therein, a curved outlet flue 15 being attached to the forward end of the said housing projecting upwardly within the vertical smokestack 16 secured to the forward portion of the locomotive 10. The smokestack 16 has a transverse partition 17 in the nature of a bottom, cutting off all communication from the interior of the

smoke box. The bottom 18 of the housing 13 is V-shaped and has a perforated pipe 19 arranged centrally thereof and extending longitudinally substantially the entire length 60 of the housing, and is provided with a controlling valve 20 exteriorly of the latter, the perforations in the pipe 19 being sufficiently large to permit the drawing of cinders and sediment therethrough from the 65 chamber 14 by means of suction.

A vertical trough-shaped conduit 21 projects transversely through the housing 13, the same being bifurcated at its lower end for straddling the pipe 19 and with its opposite side portions 22 projecting downwardly into the locomotive smoke box 12 adapted for the passage of the products of combustion therethrough, as indicated by the arrows in Fig. 1 of the drawing. The conduit 21 70 extends rearwardly along the top of the housing 13 and thence downwardly adjacent the rear end thereof forming an outlet mouth or nozzle 23. A plurality of paddle wheels 24 are journaled transversely through 75 the housing 13 within the path of travel of the products of combustion through the said housing between the outlet 23 and flue 15, the said paddles being adapted to throw and spray fluid such as 25 contained within 80 the chamber 14. The paddle wheels 24 are revolved by any desired means such as a sprocket chain 26 passing over sprockets 27 upon the shafts 28 of the said paddle wheels 24, the driving means thereof not being 85 shown.

The fluid 25 is adapted to be maintained at a substantially constant level within the housing chamber by being fed thereto through an inlet pipe 29, it being understood that the outlet valve 20 is normally closed but may be opened at the end of the run and suction applied to the pipe 19, thereby drawing sediment such as cinders, carbon and dirt through the said pipe out of 100 the washing chamber 14. This exhausting of the accumulations within the chamber 14 may take place all the time by leaving the valve on the supply pipe 29 and exhaust pipe valve 20 open. In order to clean the 105 smoke box 12 of sediment not drawn off through conduit 21, the front head 30 is removed, to give access to the smoke box, and also for cleaning flues 11. It will be seen that the products of combustion will 110 necessarily pass through or in intimate contact with the agitated fluid 25 within the

chamber 14 during the active operation of the device whereby the gases which pass to the atmosphere through the outlet flue 15 by way of the smokestack 16 will be cleaned of considerable of the impurities and foreign matter. While the present embodiments are believed to be preferable, minor changes may be made therein without departing from the spirit and scope of the 10 invention as claimed.

What I claim as new is:

A smoke washer comprising in combination with a locomotive, having a smoke stack cut off from communication therewith, a 15 housing having a washing chamber therein, a flue for the products of combustion extending into the washing chamber adjacent one

end thereof, the inlet end of said flue being bifurcated and extending into the locomotive smoke-box, fluid agitating paddles revolubly 20 mounted within the washing chamber, an outlet pipe at the opposite end of the chamber from the entrance end of said flue, the bottom of said housing being inclined downwardly toward the center, a perforated pipe 25 arranged centrally within said chamber and straddled by said bifurcated flue, a normally closed controlling valve in the perforated pipe exteriorly of the housing, a fluid inlet pipe tapped into said housing, and connection between said washer and the outlet of the smoke stack.

In testimony whereof I affix my signature.
NYKOLA PETRYK.
